UNITED STATES PATENT OFFICE

2,497,903

REFRIGERATING MECHANISM

Glenn Muffy, Springfield, Ohio

Application October 9, 1945, Serial No. 621,241

3 Claims. (Cl. 62-8)

1

This invention relates to refrigerating mechanism and particularly to such mechanism as is employed to shift refrigerant flow so as to shift refrigerating effect from one evaporator to another. This application relates to the same subject matter as my application of October 29, 1938 which resulted in U. S. Patent No. 2,359,780 which issued October 10, 1944. Reference is made to this issued patent for additional details of the herein disclosed mechanisms and their uses.

An object of this invention is to provide a valve mechanism which is actuated by a metering device responsive to the volume of refrigerant vapor flowing through a portion of the system.

Another object is to provide such a valve mechanism with a timed actuating device, the length of the operating period of an evaporator being regulated by the mass of vapor flowing therefrom.

A further object of this invention is to provide a valve mechanism within a refrigerant containing portion of the system and driven independently of any external power source.

A further object of this invention is to provide a valve timing mechanism which is responsive not only to the time and velocity of refrigerant flow but also to variations in the density of refrigerant vapor.

Other objects of the invention will become apparent from the following specification, the drawings relating thereto, and the claims hereinafter set forth.

In the drawings in which like numerals are used to designate like parts in the several views throughout:

Fig. 1 is a diagrammatic view of a self-actuating valve mechanism designed to act in response to the velocity and density of refrigerant vapor flowing from evaporators.

Fig. 2 is a simplified arrangement of the elements seen in Fig. 1.

Fig. 3 is a sectional view on the line 11-11 of Fig. 2.

The assembly seen in Fig. 1 here shown in a somewhat diagrammatic manner, illustrates the working of Figs. 2 and 3. The actuation of the valve is obtained independently of the starting and stopping of the condensing unit, being timed in relation to the density and volume of refrigerant vapor passing to suction tube 69.

As seen in Fig. 1 the port of tube 67 is open into the gas-tight casing 144, and the gas must pass through orifice 145 in the wall 146, which divides the casing 144 into two parts in a substantially gas-tight manner except for this port

2

146. The jet of gas striking vanes of the gas-wheel 147 produces rotation of this gas-wheel so long as gas is being removed through the passage 68 by action of the condensing unit. The fan (gas-wheel) is mounted rigidly upon sleeve 148, which also carries pinion 149. Pinion 149 drives gear 150, which is rigidly connected with pinion 151. This pinion drives another gear 150 and so on till the last pinion 151 drives gear 152, which is the same as gears 150 except that it is mounted on sleeve 153 instead of to another pinion. Sleeve 153 carries crank arm 154 on which is mounted the point 155. Shafts 156 and 157 are fitted freely in all of the parts through which they pass, including the cross member 158 in which shaft 156 has a bearing and wall 146 in which shaft 157 has a bearing. Sleeves 148 and 153 are free to rotate upon their respective shafts as well as in their respective bearings in wall 146 and cross-member 158, respectively.

The gear ratio and the gas-driven wheel 147 are designed to produce a very slow rotation of sleeve 153 on the order of one revolution per hour for average running conditions of gas density and velocity in the system for which the assembly is designed. The compression spring 105' is fitted with a cupped retainer at each end and held between points 155 and 102', thus being in position to hold the rocker 104' at one or the other of its two extreme positions, closing the port of 68 or 67 as the case may be. The circular travel of point 155 is on a radius such that the rocker 104' is caused to snap to the opposite position twice in each full rotation of sleeve 153. Thus each of the ports of passages 68 and 67 will be open into housing 144 alternately during a portion of a revolution of sleeve 153. As described in my earlier patent application above mentioned, this mechanism may be used to provide an ice-making period and an ice-freeing period for each of the two ice-maker evaporators. In that case the design is such that the length of an ice-freeing period is ample to provide a satisfactory ice-freeing period of the same length

45 on the opposite surfaces of the ice-maker.

Figure 1 is included for the purpose of showing the train of gearing more clearly than it can be shown in Figs. 2 and 3, which represent much more exactly the form of housing and arrangement of parts preferred in practice. The gearing seen in Fig. 2 is arranged to perform exactly the same function as the gears in Fig. 1, as do the gas-wheel 147 and the orifice 145. The dividing wall 163 serves the same function as wall 146 of Fig. 1 and in addition is the sole support for the

50

55

gearing assembly. Wall 163 fits into the lower half 164 of the gas-tight housing and is retained by the upper half 165 which is gasketed to 164 and secured together by means of screws and nuts, of which two are shown.

It is not necessary to trace the gearing between gas-wheel 147 and eccentric 167, but the gearing assembly 166 serves to produce approximately the same rate of eccentric rotation that we had of crank 154 rotation in Fig. 1. This eccentric acts upon the U-shaped arm 168 to move one end of the spring 105' first in one direction and then in the other so that it acts upon the point 102' and the valve rocker 104' exactly as before described. The slot in one side of the part 168 is non-symmetrically formed to produce about the same ratio of movement for snapping in each direction. The stop 169 attached to part 165 retains the arm 168 and prevents spring 105' from moving it too far in either direction prior to assembly of parts 164 and 165 to each other.

The type of valve mechanism illustrated by Figs. 1 to 3 inclusive is suitable for use in connection with any type of condensing unit, either intermittent or continuous in operation and of either the compression or absorption type, including adsorption systems and three-fluid systems. It has no external connection with a moving part and exposes no delicate bellows or diaphragm to the refrigerant. The cycling of the evaporators is thus independent of the cycling of the condensing unit. It may be desired to regulate the operation of the condensing unit to stop it when a maximum supply of ice has been accumulated or a minimum low temperature attained but this stopping and starting need not be synchronized with the cycling of evaporators during one running period. A thermostatic control may be made subject to cabinet air temperature independently of evaporator temperature, providing a more uniform cabinet air temperature control than is possible with any of the conventional thermostatic controls.

On account of the very light load on the fast-moving parts and the very slow motion of the more heavily loaded parts, it is possible to operate the valve mechanisms with practically no lubrication, but some lubrication is obtained from the

refrigerant itself and more from the oil which circulates with the refrigerant in most systems. The outlet at 69 may be so located that some oil is trapped within the gear housing in position for one or more of the gears to dip in this oil. Such an arrangement is shown in Fig. 1. Bearings of Figs. 2 and 3 may be hardened or jewelled or made of a self-lubricating material such as a graphite-impregnated bronze, or they may be of ball or roller types which will operate under these light loads with no lubrication.

What is claimed is:

1. In a refrigerating system, means forming a refrigerant circuit including alternate paths for refrigerant flow, valve means for diverting refrigerant flow from one to the other of said paths, and mechanical means driven by refrigerant flowing through said system for actuating said valve means at timed intervals.
- 15 2. In a refrigerating system, means forming an enclosure adapted to contain a refrigerant, a rotary member driven by the flow of refrigerant within said enclosure, and a control device actuated by said rotary member at a frequency of operation much lower than the frequency of rotation of said member.
- 20 3. In a refrigerating system, a refrigerant, means forming a flow circuit for said refrigerant including an enclosure through which said refrigerant flows during operation of said system, a rotary member within said chamber adapted to be driven by the flow of said refrigerant, and means actuated by said member to change the path of said refrigerant in its flow through a portion of said system.
